Term of patent 3½ years

(Cl. D87—3)

Fig. 1.

Fig. 2.

To all whom it may concern:

Be it known that I, Lee T. Bordner, a citizen of the United States, residing at Los Angeles, in the county of Los Angeles and State of California, have invented a new, original, and ornamental Design for Parasol Handbag, of which the following is a specification, reference being had to the accompanying drawing, forming part thereof.

In the drawing:

Fig. 1 is a perspective view of the parasol handbag in closed position, showing my new design; and

Fig. 2 is a perspective view of the parasol handbag opened.

The side of the parasol handbag not shown in the drawing is identical with the side shown.

I claim:

The ornamental design for a parasol handbag, substantially as shown and described.
